UNITED STATES PATENT OFFICE.

WALTER HYDE, OF OAKLAND, CALIFORNIA.

SWING.

SPECIFICATION forming part of Letters Patent No. 277,902, dated May 22, 1883.

Application filed November 24, 1882. (No model.)

To all whom it may concern:

Be it known that I, WALTER HYDE, a citizen of the United States, residing at Oakland, in the county of Alameda and State of California, 5 have invented certain new and useful Improvements in the Construction and Arrangement of Swings, of which the following is a specification, reference being had to the accompanying drawings.

10 Figure 1 is a side elevation; Fig. 2, a part elevation; and Figs. 3 and 4 are plan views, showing the attaching-irons from which the swing is suspended.

I employ a wooden or metallic horse, A. 15 (Shown in Figs. 1 and 2.) To the breast of this horse I attach an iron (shown in position in Figs. 1 and 2) by means of screw-bolts. The ends of this iron extend sufficiently to carry the ropes by which the forward part of the 20 horse is supported sufficiently out of the way to clear the body of the person who sits upon the horse when swinging. The irons C, which are attached to the side as far back as a solid attachment may be had and the best effect of 25 strength and durability maintained, extend sufficiently back and outward, as well as upward, to carry the ropes clear of the person occupying the seat upon the horse. The eyes of the attaching-irons B and C are arranged to 30 receive the rings K and L in the position shown, so as to rock on their bearings in the eyes of the attaching-irons, and prevent any grinding or slipping motion. To these rings are attached the ropes D and E, and at the 35 upper ends of these ropes are also attached the rings M and N, to operate in the hooks J with the same rocking motion. These hooks J are attached to the beams G by means of a base plate or bar, which may be constructed 40 of two parts, with an adjusting-slot, O. The hook-plates T and V are generally adjusted so as to place the hooks about ten or twelve inches apart forward and back and about two feet apart laterally. The object of arranging 45 these hooks forward and back is to secure an approximate parallel position of the body of

the horse, as it will be readily understood that when the hooks are arranged farther apart to approach the distance at which the rings K and L are placed the rings K and L will be 50 kept near at a level at each part of their arcs of vibration.

This device secures the regulation of the rocking motion of the horse, to increase or diminish the same as the rider wills by pulling 55 and pushing the ropes by the handles W, which are attached to the forward ropes.

The rings K and L, M and N, being arranged to roll in their bearings, save the ropes from wearing or cutting, as is the case when the rope 60 is allowed to slide at its point of attachment. The length of ropes may be varied to suit, although I find about twelve feet the most suitable length. I adjust them by a slip-knot, H, which allows the immediate lengthening or 65 shortening, as may be required.

The following is the operation of the same: The child or other person, when swinging, sits upon the saddle-cloth, placing the foot in the stirrup, the hands grasping the hand-holds W. 70 By pulling the horse moves forward, and by pushing a backward motion is given to the same. The hook F being placed forward and the hook J back sufficiently apart prevents the head and tail of the horse from being swung 75 alternately too high as the same swing forward and back; but where it is found desirous to increase the rocking motion these hooks J may be brought nearer together, thus causing a greater rocking motion, and vice versa. 80

Having thus described my invention, what I claim is—

The horse A, with the attaching-irons B and C, the rings K and L, the ropes W, D, and E, the rings M and N, hooks F and J, and hook-plates V and T, the whole being combined and operated substantially as and for the purposes set forth. 85

WALTER HYDE.
